UNITED STATES PATENT OFFICE.

HENRY F. MARTINEAU, OF SOLVAY, NEW YORK.

GRATE.

Application filed January 20, 1925. Serial No. 3,573.

This invention relates to a fire box grate for locomotive boilers and other heating apparatus having relatively large combustion chambers for burning soft coal and other 5 solid fuels.

In the use of grates commonly employed in heating apparatus of this character the slag or molten clinkers accumulating upon the surface of the grate tend to obstruct the 10 draft or free flow of air from the ash pit through the fuel to such an extent as to greatly reduce combustion of the fuel with the result that it is difficult to maintain the desired steam pressure for any long period 15 of time without entirely withdrawing the fuel and cleaning the grates from these obstructions, thereby making it necessary to frequently remove the engine from service for cleaning purposes, all of which adds 20 materially to the operating expenses and imposes unnecessary delays and inconveniences on the operators and general public.

The main object of this invention is to reduce these difficulties to a minimum by providing a grate of such character that the 25 slag or molten clinkers may be more effectively broken up by the operation of the grate bars.

In other words, I have sought to construct 30 the grate bars in such manner that when turned by any suitable operating means different portions of each bar and also of adjacent bars will be brought to different levels thereby causing a similar movement 35 of the slag or molten clinkers for breaking up the continuity of the more or less molten mass into sufficiently reduced sizes to enable the broken parts to fall through the grates into the ash pit and thereby to maintain 40 a more efficient draft of air through the fuel with the result that the locomotive or other apparatus equipped with this grate may be run continuously for a longer period of time than has heretofore been practised.

45 Other objects and uses relating to specific parts of the device will be brought out in the following description.

In the drawings:

Figure 1 is a perspective view of the 50 tached grate and its supporting frame, the grates of one series being fully opened and the set of grates closed.

Figure 2 is a longitudinal vertical sectional view taken on line 2—2, Figure 1.

Figure 3 is a transverse, vertical sectional view taken on line 3—3, Figure 1.

As illustrated this grate comprises a substantially rectangular frame —1— and a plurality of series or sets of grate bars, the frame —1— being provided with a central 55 lengthwise partition —1'— of substantially the same height as the remaining portions of the frame.

The opposite sides and intermediate partition of the frame are provided with journal bearings —3— for receiving suitable 60 trunnions as —4— on the ends of the grate bars of each set.

These grate bars are arranged to revolve in their respective compartments about 70 parallel axes transversely of the frame —1— and inasmuch as the compartments are of substantially the same width the grate bars in each compartment are of corresponding 75 length to extend from side to side of the compartment in which they are located.

That is, the grate bars of each set revolve about axes in uniformly spaced relation 80 lengthwise of the frame or from front to rear and the axes of the bars of each set are preferably alined with the axes of the opposite bars of the other set so that the corresponding bars of each set are movable about the same axis and are therefore arranged 85 end to end in substantially the same horizontal plane.

The several bars of each set are provided substantially midway between their ends with crank arms —5— projecting therefrom in the same general direction pivotally connected to an operating rod or bar —6— for simultaneously rocking movement about their respective axis, said operating bar being extended forwardly beneath the grate bars and through openings —7— in the front and rear sides of the frame as shown more clearly in Figures 2 and 3, the front ends of the bars being adapted to be connected to any well-known form of operating lever not necessary to herein illustrate or 100 describe.

The grate bars of each set are preferably tapered from end to end but are arranged in reverse order so that alternate bars taper in

one direction and the remaining bars of the same set taper in the opposite direction but when closed cover substantially the entire area of the compartment in which they are located for a slight clearance which is left between the meeting edges thereof.

The edges of the end bars of each set adjacent the end walls of the frame —1— when the grate bars are closed are substantially parallel with the axes of movement of the several bars so as to entirely close with the adjacent ends of the frame when closed, the inner edges of the same end bars being arranged at an angle to said axes or diagonally of the frame.

Both edges of the intermediate bars of each set are disposed at equal angles to their axes of rotation and are of equal taper but reversely arranged as previously explained, the angle of inclination of the inner edges of the end bars being equal to that of the edges of the intermediate bars relatively to their axes of movement.

Under these conditions each bar will be considerably wider at one end than at its opposite end and the smaller ends of alternate bars will be interposed between the larger ends of the remaining bars and it therefore follows that when the grate bars of each set are closed they will lie in substantially the same horizontal plane, but when opened the upper edges will lie in inclined planes, those of adjacent bars inclining in opposite directions as shown more clearly in Figures 1 and 3.

That is, when the bars of either set are opened, the wider ends of alternate bars will project some distance above the corresponding ends of the other bars, thus producing high and low supporting points alternating with each other at both ends of the bar of each set, the purpose of which is to break up the continuity of the slag or molten clinkers which may rest upon the bars whereby the broken pieces may readily pass downwardly between the bars into the ash pit to enable the air to circulate freely through the fuel for combustion purposes.

The crank arms —5— constitute reinforcing ribs for the grate bars and are preferably curved along their outer edges to permit the free movement of the bars from their closed to their open positions and vice versa without frictional contact with the crank arms and at the same time permitting the grate bars to be assembled in relatively close proximity to each other. The journal bearings —3— in the upper edge of the partition —1'— are preferably open at the top to permit the grate bars to be removed and replaced at will, it being understood that the bearings —3— in the side walls of the frame —1— are sufficiently large to permit this displacement and replacement of the bars.

The construction of the grate bars of uni-

form taper enables them to be interchanged from side to side and used in either compartment without alteration.

Operation.

When the bars are closed as shown in one of the compartments in Figures 1 and 3, the space between the adjacent edges thereof allows sufficient draft or the passage of sufficient air from the ash pit to the fuel to support combustion, but if the slag or molten clinkers should accumulate on the closed grate sufficiently to interfere with the free draft of air therethrough the grates of either set or both sets may be turned to the position shown in the upper part of Figure 1 thereby lifting the portions of the slag engaged with the high parts of the bars and allowing the intervening portions to fall back on the low edges of the intervening bars which is ordinarily sufficient to break up the slag to such an extent as to allow the pieces to fall through the intervening spaces between the bars and if the slag is not sufficiently broken up by the first opening of the bars the operation may be repeated until the desired result is accomplished.

This breaking up of the slag is greatly facilitated by the reverse inclination of the edges of adjacent bars which prevents any uniform sag of the slag between alternate bars from end to end thereof, the degree of elevation and depression of the bars depending upon the extent to which they are opened as controlled by the forward and rearward movement of the operating member —6—.

It is, of course, obvious that if the operation of one set of bars does not properly break up the slag the other set may be similarly operated to complete the disintegration of said slag sufficiently to allow it to fall through the openings between the bars.

The construction shown is particularly simple and efficient but it is evident that various changes may be made in the detailed constructions of the frame and grate bars and other parts of the device without departing from the spirit of this invention.

What I claim is:

1. A grate comprising a frame, grate bars journaled side by side at their end in the frame to swing about parallel axes, said bars being substantially less in thickness than in either length or width, adjacent bars being tapered in opposite directions lengthwise of their axes.

2. A grate as in claim 1 in which all of the bars are provided with crank arms on one and the same side thereof and an operating bar pivotally connected to the crank arms.

3. A grate comprising a frame having a lengthwise partition dividing it into separate compartments, separate sets of grate bars arranged side by side in said compartments,

those of each set having their outer ends journaled in the outer walls of the frame, and their inner ends journaled in the partition so that the bars of each set are free to swing about parallel axes, adjacent bars of each set being tapered in opposite directions lengthwise of their axes, said bars being substantially less in thickness than in either length or width.

40. 4. A grate as in claim 3 in which the grate

bars of each set are provided with crank arms depending from one and the same side thereof and separate operating bars one for each set of grate bars and each pivotally connected to the crank arms of its corresponding set.

In witness whereof I hereunto set my hand this 6th day of January, 1925.

HENRY F. MARTINEAU.
